DECORATIVE PIPING STRIPS

Theodore J. Boecker, Winchester, Mass., assignor to Boecker-Stuart, Inc., Cambridge, Mass., a corporation of Massachusetts

Application September 5, 1952, Serial No. 308,116

5 Claims. (Cl. 154—53.6)

This invention relates to improvements in decorative piping strips which are suitable for ornamenting or finishing upholstery and leather and imitation leather products but which have especial utility as decorative piping for moccasin type shoes and slippers. More particularly, the invention provides such piping strips which may be manufactured with a substantial saving of material as compared with the comparable piping strips produced according to prior procedures.

Decorative piping strips of the variety to which the invention relates have a bead strip of leather, woven cord, or other suitable material, exposed at intervals along that edge of the piping strip which is visible in a shoe or other article. The piping strip is wrapped around the bead strip but has spaced openings through which the bead strip is exposed.

Heretofore, the initial strip of material of which the piping strip is formed has been uniformly perforated with relatively large holes or cut-outs distributed uniformly throughout the length of the strip, and when this perforated strip is wrapped around a bead strip, portions of the latter are exposed where they cross the perforations, to provide a beaded edge having decorative character. However, the stock cut out to provide the substantial perforations is entirely wasted.

It is among the objects of the invention to provide decorative piping strips having all of the decorative attributes of the prior comparable strips, but which may be produced more economically without any wastage of material. According to the invention, two similar rameose strips simultaneously are cut or dinked in a manner to utilize all of the material of the initial strip, each rameose strip having uniformly spaced tongues adapted to be wrapped around a bead strip to produce the same decorative effect attained with the prior perforated strips.

Another object of the invention is to provide an intermediate product in the production of decorative piping strips comprising a rameose strip of flexible sheet material having relatively long uniformly spaced tongues whose end portions are connected together by a relatively narrow strip of flexible material adhered to one side of the end portions of all of the tongues, whereby the uniform spacing of the tongues is maintained as they are successively wrapped around a bead strip.

A further object of the invention is to provide a rameose strip of flexible sheet material having relatively long uniformly spaced tongues projecting from an intact marginal portion of the strip, the tongues being adapted to be wrapped around a bead strip in the manufacture of decorative piping strips, and the ends of all of the tongues being connected by a relatively strong strip adhered to the end portions of all of the tongues and adapted to be adhered to said intact marginal portion of the first mentioned strip when said tongues are wrapped around the bead strip, thereby to constitute a reinforcement through which stitches may pass when the decorative piping strip is being secured in a shoe or other article.

It is, moreover, my purpose and object generally to improve decorative piping strips, and the procedures of manufacturing such strips.

In the accompanying drawing:

Fig. 1 is a plan view of a strip of flexible sheet material showing how two of my rameose strips may be cut or dinked therefrom without wastage of any material;

Fig. 2 is a perspective of one of my rameose strips

having adhesive material coating the upper surface thereof and having a relatively narrow strip of material adhered to the end portions of all of the tongues of the rameose strip;

5 Fig. 3 is a view similar to Fig. 2 showing the tongues of the rameose strip, with the narrow strip thereon, turned inward and adhered to the intact marginal portion of the rameose strip, the tongues being wrapped around a bead strip which is omitted excepting at the left hand portion of Fig. 3;

Fig. 4 is a cross-sectional view on line 4—4 of Fig. 3;

Fig. 5 is a view similar to Fig. 2 but showing the narrow strip adhered to the end portions of the tongues at their under sides, whereby this narrow strip may be stripped off after the tongues have been turned over a bead strip and adhered to the intact marginal portion of the rameose strip;

Fig. 6 is a view similar to Fig. 5 but showing the majority of the tongues after being turned inward and adhered, and showing the left hand end portion of the narrow strip in the process of being stripped from the tongues;

Fig. 7 is a cross-sectional view on line 7—7 of Fig. 6;

Fig. 8 is plan view of a fragment of a completed decorative piping strip embodying a cross-sectionally round bead strip;

Fig. 9 is a perspective of a portion of the forepart of a moccasin type shoe having my improved piping strip embodied therein; and

30 Fig. 10 is a plan view of a fragment of a prior comparable piping strip with its bead strip shown in partially wrapped condition.

Referring to the drawing, the decorative piping strips of the invention are rameose strips 10, of leather or other suitably flexible material, having the relatively long tongues 10^a extending in uniformly spaced parallelism, with each space 10^b between adjacent tongues complementary to a tongue 10^a, whereby two of the rameose strips 10 may be cut, as by a dinking die, from a single wider strip 12 (Fig. 1), without any of the material of strip 12 being wasted.

Heretofore, such decorative piping strips have been made, as illustrated in Fig. 10, by cutting or dinking spaced holes 14 in a strip 12^a which usually is 1½" or 1¾" wide. The stock cut out to form the holes 14 is wasted.

According to the invention, two of the rameose strips 10 are cut or dinked from a strip 12 which may have width as little, or less than 1½", and the entire strip 12 is utilized, with substantial saving in material as compared with the prior procedures.

The flesh side of each rameose strip 10, assuming the strips to be of leather, is coated with a suitable adhesive which is indicated by the stippling at 16 in Figs. 2—6, adhesive on the prior strip of Fig. 10 also being indicated by stippling at 16^a. The adhesive 16 may be rubber cement, or latex or any other suitable adhesive, and it may be coated all over the flesh side of the rameose strips 10, or may be coated only along the edge portion at the base of the tongues 10^a and at the tip portions of the tongues, as shown in Fig. 5. In either case, the tongues 10^a may be folded inward over a bead element 18 (Figs. 3, 6, 8 and 9) with the in-turned end of each tongue becoming adhered in its in-turned condition, and with the bead element 18 exposed at the regions where it crosses the spaces between tongues 10^a.

Referring more particularly to Figs. 5 and 6, an adhesive strip 20 is shown adhered to the grain or finished side of a rameose strip 10, joining together the end portions of all of the tongues 10^a of the strip. The strip 20 may, for example, be a strip of scotch tape, or the like, which readily may be adhered to the tongues as in Fig. 5, thereby to aid in maintaining the spaced relation of the tongues and to facilitate inturning of the tongues to their secured positions of Fig. 6, after which the adhesive strip 20 may be stripped off. The bead element 18, over which the tongues engage in spaced relation may be a strip of leather, as in Figs. 3 and 6, or may be a woven cord, or the like, as shown in Fig. 8. It should be understood that the adhesive strip 20 of Figs. 5 and 6 may be omitted, if desired, but its presence

facilitates in-turning of the spaced tongues 10^a by conventional or other in-folding machinery, or by hand.

Figs. 2 and 3 illustrate an adhesive strip 22 adhered across the end portions of the tongues 10^a at the flesh side or coated side of the strip and tongues, and this strip 22 becomes a permanent part of the ornamental piping strip inasmuch as it becomes engaged between the un-cut edge portion of the strip and the in-turned end portions of the tongues 10^a. Here again, the strip 22 serves primarily to facilitate in-turning of the tongues, especially when the in-turning is accomplished by machine. However, the adhesive strip 22 may be a fabric strip of a nature to reinforce and strengthen the securing of the piping strip in a shoe, in that the stitches at 24 (Fig. 9) may pass through this reinforcing strip 22.

It will be apparent from the foregoing description, in connection with the drawing, that my improved decorative piping strips may be produced with substantial savings as compared with the prior comparable piping strips, and may be incorporated in shoes, and other articles, to serve in the same manner and with the same decorative effects as the prior more expensive piping strips. Also, when a reinforcing fabric strip 22 is employed, as in the Figs. 2 and 3 embodiment, the fabric strip 22 substantially strengthens the stitched securing of the piping strip in a shoe, or other article.

It is intended that the patent shall cover by suitable expression in the appended claims whatever features of patentable novelty exist in the invention disclosed.

I claim as my invention:

1. A decorative piping strip comprising a ramoso strip of flexible sheet material having relatively long tongues of the flexible material extending in spaced relation from an integral substantially intact marginal portion of the ramoso strip, a bead element disposed along the ramoso strip and crossing the spaces between said tongues in substantially spaced relation to said marginal portion of the ramoso strip, all of said tongues being turned inward over said bead element, and means securing the in-turned end portion of each tongue to said substantially intact marginal portion of the ramoso strip, whereby said bead element is secured to the ramoso strip and has exposed extent between adjacent in-turned tongues in the said substantially spaced relation to said marginal portion of the ramoso strip.

2. A decorative piping strip comprising a ramoso strip of flexible sheet material having relatively long tongues of flexible material extending in spaced relation from an integral substantially intact marginal portion of the ramoso strip, each space between adjacent tongues being complementary to a said tongue whereby each said space may be formed by removal therefrom of a tongue of a second ramoso strip, a bead element disposed along the ramoso strip and extending across all of the tongues thereof and across all of the spaces between the tongues in substantially spaced relation to said marginal portion of the ramoso strip, a relatively narrow strip of flexible material adhered to end portions of all of said tongues, said end portions of all of the tongues, with said narrow strip thereon, being turned inward over said bead element and secured to said substantially intact marginal portion of the ramoso strip with said bead element exposed between said tongues in its said substantially spaced relation to said marginal portions of the ramoso strip.

3. A decorative piping strip comprising a ramoso strip of flexible sheet material having relatively long tongues of the flexible material extending in spaced relation from an integral substantially intact marginal

portion of the ramoso strip, an adhesive substance on one side of said ramoso strip, a relatively narrow strip of flexible material adhered to end portions of all of said tongues at that side thereof which has the said adhesive substance thereon, a bead element disposed along the ramoso strip and extending across all of said tongues and across all of the spaces between tongues at that side of the ramoso strip which has said adhesive substance thereon, the said bead element being in substantially spaced relation to said marginal portion of the ramoso strip, said relatively narrow strip, which has the end portions of all said tongues adhered thereto, being turned over upon the adhesive-coated substantially intact marginal portion of the ramoso strip thereby to wrap said tongues in spaced relation around said bead strip, with portions of the bead strip exposed in the spaces between adjacent tongues and in the said substantially spaced relation to said marginal portion of the ramoso strip.

4. A decorative piping strip comprising a ramoso strip of flexible sheet material having relatively long tongues of the flexible material extending in spaced relation from an integral substantially intact marginal portion of the ramoso strip, an adhesive substance on one side of said substantially intact marginal portion of the ramoso strip and on the end portions of all of said tongues, whereby the ends of the tongues may be turned inward and be adhered to said substantially intact marginal portion of the ramoso strip, a relatively narrow strip of flexible material adhered to the end portions of all of said tongues at that side thereof opposite the side having said adhesive substance thereon, a bead element disposed along the ramoso strip and crossing all of the spaces between said tongues at that side of the tongues which has said adhesive substance thereon, the said bead element being in substantially spaced relation to said marginal portion of the ramoso strip, all of said tongues, with said narrow strip secured thereon, being turned inward over said bead element and adhered to said substantially intact marginal portion of the ramoso strip with said narrow strip exposed at outer surfaces of the in-turned tongues in position to be stripped from the secured tongues, and with said crossing portions of said bead element exposed between the tongues in said substantially spaced relation to the marginal portion of the ramoso strip.

5. In a decorative piping strip, a ramoso strip having spaced tongues projecting from an intact marginal portion of the ramoso strip and having each space between adjacent tongues complementary to a said tongue whereby two similar ramoso strips may be died simultaneously from a wider strip with utilization of all of the material of said wider strip, said tongues of the ramoso strip being turned inward and having their end portions secured to said intact marginal portion of the ramoso strip, thereby to provide spaced loops of the strip stock outward of said intact marginal portion through which loops a linear element may be passed with portions thereof exposed between the said loops in spaced relation to said intact marginal portion of the ramoso strip.
